UNITED STATES PATENT OFFICE.

ERIC H. LEN, OF LOS ANGELES, CALIFORNIA.

CARPENTER'S TOOL.

1,056,917.

Specification of Letters Patent. Patented Mar. 25, 1913.

Application filed April 25, 1912. Serial No. 693,191.

To all whom it may concern:

Be it known that I, ERIC H. LEN, a subject of the King of Sweden, residing at Los Angeles, in the county of Los Angeles, State of California, have invented a certain new and useful Carpenter's Tool; and I do hereby declare the following to be a full, clear, and exact description of the invention, such as will enable others skilled in the art to which it appertains to make and use the same.

This invention relates to a carpenter's tool, more particularly to one adapted to be conveniently used to mark or scribe the notches or housings usually made in the strings of stairs to receive and hold therein the end portions of the riser and tread of the steps, and it may be said to consist in the provision of the novel features, and in the novel and improved construction, arrangement and combination of parts in the tool as will be apparent from the description and claim which follow hereinafter.

Objects of the invention are to provide a novel and improved tool of the nature specified, which is simple in construction, economical to manufacture, easily and quickly adjustable, strong and durable, and convenient and effective in use.

Other objects and the advantages of the invention will be apparent to those skilled in the art from a consideration of the following description of the preferred form of construction embodying the invention taken in connection with the accompanying drawings, in which—

Figure 1 is a perspective view of the tool, the nosing block being omitted; Fig. 2 is a view of parts that may be used for holding and locking in position the straight edge on the angle part, and Fig. 3 is a partial perspective view of the angle part, showing the nosing block attached thereto.

The straight edge 2 may be provided rearwardly thereof with a suitable handle 3. In the end portions of the straight edge 2 are provided slots 4 which extend from the front to the rear of the straight edge, and slots 5 which extend through the upper and lower sides of the straight edge and communicate with the slots 4. The angle part 6, preferably steel, may be formed to provide the legs 7 and 8 having the outer edges 9 and 10 thereof formed straight and

disposed at right angles to each other, and the extension 11 of the leg 7 which extends beyond the outer edge 10 of the leg 8 and is adapted for marking the nosing on the tread of the steps of the stairs. Both sides of the legs 7 and 8 at the outer edges 9 and 10 thereof may have thereon suitable graduations 12 of linear measure.

In order to readily mark notchings which are to receive wedges to hold the steps in the strings, the legs 8 may be formed to have the inner edge 13 thereof suitably slanting, and the leg 7 may have the inner edge portion 14 thereof split, see Fig. 1, to provide the portion 15 which may be sprung from the main portion of the leg 7 to provide the desired slant of the inner edge 16 of the leg 7. The free end of the portion 15 may have pivotally connected thereto one end of the screw 16' which passes through an adjusting nut 17 suitably mounted on the main portion of the leg 7 so that by turning the nut 17 the slant of the inner edge 16 may be varied at will.

As seen in Fig. 1, the legs 7 and 8 pass freely through the slots 4 and are provided with longitudinal slots 18. Any suitable means may be employed to lock the legs 7 and 8 in adjusted position in the slots 4 of the straight edge 2; that shown consisting of a threaded pin 19, adapted to pass through the slots 5 and 18 and provided with a head 20 and a squared portion 21 adapted to fit in the slots 5, and a nut 22 which fits the pin 19 and may be turned to permit adjustment of the legs 7 and 8 in the straight edge 2 and to lock the legs and straight edge in adjusted position.

In order that the various forms of nosings for the tread of the steps may be easily marked, the leg 7 may be provided with slots 23 adjacent to the extension 11, whereby a block 24 having the desired form of nosing 25 thereon may be secured to the leg 7 by means of screws 26 passing through the slots 23.

From the foregoing the use of the tool will be readily understood by those skilled in the art, it being apparent that the straight edge 2 may be placed against the lower edge of the string and the legs 7 and 8 respectively adjusted to the width of the tread and the height of the riser of the steps, whereupon the notchings in the string may

be marked in the well-known manner by moving a scribe along the inner and the outer edges of the legs 7 and 8.

I claim:

5 A carpenter's tool consisting of a straight edge provided with slots therethrough, an angle part having graduated legs passing through said slots, said legs having the outer edge thereof straight, one of said legs having
10 an adjusting nut mounted thereon and having the inner edge portion thereof split, a screw pivotally connected with the free end of said inner edge portion and passing through said

adjusting nut, and one of said legs having slots therein for screws to hold a block having the desired form of nosing, substantially 15 as described.

In testimony whereof, I have signed my name to this specification in the presence of two subscribing witnesses at Los Angeles, 20 county of Los Angeles, State of California, this 19th day of April A. D. 1912.

ERIC H. LEN.
